UNITED STATES PATENT OFFICE.

ANTON E. EISENMANN, OF HAMILTON, OHIO, ASSIGNOR OF ONE-HALF TO LOUIS WEIS,
OF HAMILTON, OHIO.

TOOL-HOLDER.

1,235,298.

Specification of Letters Patent.

Patented July 31, 1917.

Application filed February 16, 1917. Serial No. 148,957.

To all whom it may concern:

Be it known that I, ANTON E. EISENMANN, a citizen of the United States, residing at Hamilton, Butler county, Ohio, have 5 invented certain new and useful Improvements in Tool-Holders, of which the following is a specification.

This invention pertains to toolholders employed on machine tools, the toolholder being of that class in which the tool is put into clamped connection with a T-slotted tool-block in such manner that the tool, before being clamped to the tool-block, may be angularly adjusted. In the commoner form 10 of toolholders employed in American machine tool practice, a mortised tool-post serves as a means for clamping the tool and as the pivot on which the tool may be angularly adjusted, the tool-post thus serving as 15 a clamping-member for the tool and as the pivot on which it may be angularly adjusted. In somewhat similar toolholders, often spoken of as English toolholders, and much employed in Europe, the tool does not pass 20 through the member providing for the pivotal adjustment but is disposed and clamped alongside that member. I illustrate my invention in a tool-post of the American type.

The invention will be readily understood 25 from the following description taken in connection with the accompanying drawing in which:

Figure 1 is a side elevation of the improved toolholder;

Fig. 2 a horizontal section of the same in the plane of line *a* of Figs. 1 and 3;

Fig. 3 a vertical section of the same in the plane of line *b* of Figs. 2 and 4; and

Fig. 4 a bottom view of the sub-collar.

40 In the drawing:

1, indicates the usual tool-block:

2, the usual T-slot in the top thereof:

3, the usual American mortised tool-post:

4, the usual T-shaped head on the lower 45 end of the tool-post engaging the T-slot in the tool-block:

5, a sub-collar surrounding the tool-post and resting on the top of the tool-block:

6, a rib projecting downwardly from the 50 sub-collar and fitting into the slot in the tool-block so that the sub-collar is incapable of angular motion on the tool-post:

7, a super-collar surrounding the tool-post and resting on the sub-collar:

55 8, coöoperating radial serrations on the

contiguous faces of the super-collar and sub-collar, these serrations being formed with sharp edges and angular sides and serving to normally prevent the angular movement of the super-collar on the sub- 60 collar, while permitting angular adjustment to be made when the super-collar is elevated sufficiently to disengage the serrations:

9, a groove formed diametrically in the 65 top of the super-collar, in line with the mortise in the tool-post, and of a width sufficient to accommodate the tool, the floor of this groove being formed on an upwardly concave curve:

70 10, the so-called wedge, seating in the groove 9 of the super-collar and passing through the mortise in the tool-post with its top below the top of the super-collar, the lower surface of this wedge being convex to fit the concavity of the floor of the groove, and the top of the wedge being preferably serrated or roughened to form a biting seat for the tool:

75 11, transverse serrations on the floor of 80 the groove in the super-collar and on the bottom of the wedge; and

12, the usual mortise through the tool-post.

When the tool-holding parts are in the 85 position indicated in the drawing and a tool is clamped in the tool-post, the tool will be level and lie in a plane at right angles to the slot in the tool-block. By adjusting the wedge, in the usual manner, the 90 point of the tool may be raised or lowered before the tool is clamped and the serrations 11 prevent downward movement of the point of the tool. When the tool is clamped in place its point cannot shift 95 sidewise owing to the engagement of the sides of the body of the tool with the side walls of the slot in the super-collar. But, before clamping the tool, the super-collar may be raised to free the serrations 8 and 100 to permit it to be adjusted angularly upon the sub-collar, thus giving a horizontal angular position to the tool, and when it is clamped in place its angular position cannot be disturbed because the walls of the 105 slot prevent the angular shifting of the tool with reference to the super-collar, and the serrations 8 prevent the angular shifting of the super-collar with reference to the sub-collar, and the rib 6 prevents the angular 110

shifting of the sub-collar with reference to the tool-block. When the super-collar is being adjusted angularly upon the sub-collar, to give angular position to the tool, the tool-post turns in the tool-block in the usual manner and the sharp character of the teeth prevents the lodgment of the super-collar at points between the step by step adjustments, the angular sides of the teeth preventing any possibility of their angular shifting with reference to each other after adjustment.

I claim:

1. In a tool-holder, a perforated sub-collar having upon its lower surface a projecting rib and provided upon its upper surface with radial serrations formed of teeth with sharp edges and angular sides, substantially as set forth.
2. A structure as specified in claim 1 in combination with a tool-block provided with a T-slot in which the rib of the sub-collar may slide, a perforated super-collar adapted to give support to a tool and provided upon its lower surface with radial

serrations coöperating with the serrations of the sub-collar, and a clamping pivot-member passing through the perforations in the two collars and into the slot of the tool-block and angularly movable with reference to the tool-block and sub-collar, substantially as set forth. 30

3. A structure as specified in claim 2 in which the pivot-member is transversely mortised and in which the upper surface of the super-collar is grooved in line with the mortise of the pivot-member, substantially as set forth. 35

4. A structure as specified in claim 3 in which the floor of the groove in the super-collar is concave and transversely serrated in combination with a wedge seated in the groove of the super-collar and having its under surface transversely serrated, substantially as set forth. 40

ANTON E. EISENMANN.
